UNITED STATES PATENT OFFICE.

JAMES BARKER, OF PHILADELPHIA, PENNSYLVANIA, ASSIGNOR TO MARY EMMA BARKER, OF RYDAL, PENNSYLVANIA.

DOFFER-ROLL.

1,286,497.

Specification of Letters Patent. Patented Dec. 3, 1918.

Application filed May 16, 1917. Serial No. 163,994.

To all whom it may concern:

Be it known that I, JAMES BARKER, a citizen of the United States, residing in Philadelphia, Pennsylvania, have invented certain Improvements in Doffer-Rolls, of which the following is a specification.

My invention relates to certain improvements in doffer rolls used in carding and like machines.

10 The object of the invention is to provide means for retaining the card clothing on the roll so as to prevent it from slipping while the machine is in operation.

In the accompanying drawing:

15 Figure 1 is a transverse sectional view through one-half of a doffer roll;

Fig. 2 is a side view of the roll with the card clothing in section;

20 Fig. 3 is an enlarged sectional view through one of the channels in the cylinder in which the tacking strip is located, and

Fig. 4 is a sectional view on the line 4—4, Fig. 3.

25 Referring to the drawings, 1 is the cylinder having a series of longitudinal slots or channels 2 therein and spaced a given dis-

tance apart, as clearly shown in Fig. 1. In each channel is located a tacking strip 3 of wood, or other suitable material. This strip can be driven into the channels or can 30 be secured therein in any suitable manner. 4 is the leather base of the card clothing in which are located the usual teeth 5. Tacks, or other suitable fastenings 6, are driven through the leather and into the strips 3 35 and these fastenings prevent the card clothing from creeping on the cylinder. They not only hold the card clothing against relative movement on the cylinder, but also against lateral movement thereon. 40

I claim:

The combination of a doffer cylinder having a series of parallel grooves extending transversely from one edge of the cylinder to the other across its face; a wooden strip 45 mounted in each groove; card clothing covering the said cylinder; and headed tacks driven through the card clothing and into the strips after the clothing is in place and retaining the clothing firmly on the cylinder. 50

In witness whereof I affix my signature.

JAMES BARKER.
